MUSICAL INSTRUMENT

**Melvin L. Severy, Los Angeles, Calif., assignor to
The Vocalseviro Company, Los Angeles, Calif.,
a corporation of Delaware**

Application July 15, 1931, Serial No. 550,987

13 Claims. (Cl. 84—331)

This invention relates more particularly to a musical instrument having a plurality of tone qualities synthetically built up of suitably chosen and graded partials, each partial being produced 5 in the air through the agency of a pulsated electromagnetic field including a movable member and a co-acting magnetizable member adapted to vibrate a sonorous element. It is not, however, restricted to such use, since the requisite pulsations may be produced through revolving commutators and brushes coacting therewith, such as disclosed in my Patent No. 1,733,630 and in my co-pending application Serial No. 545,611 filed June 19, 1931.

15 An important object of the invention is the production of a musical instrument of one or more manuals, which is relatively cheap, compact, and durable, exceedingly powerful, exceptionally diversified as to tone, and of unusual artistic capabilities.

Another important object of the invention is the production of an instrument having a plurality of manuals adapted to be simultaneously put under the command of a single player or of a 25 plurality of players, thus in the latter case, multiplexing the instrument as it were. These manuals may be operated by a roll or mechanically, from a central console and by a single player. It is further possible to operate any one of the 30 consoles or all of them, by rolls individual to each console with an operator for each roll or mechanical device for playing, the synchronization being left to the players or operators, as in ordinary playing.

35 A further important object of the invention is the provision of multiplexed sonorous members, each such member capable of responding at its own proper pitch when any one of a plurality of manuals is played, thus cheapening, simplifying, and greatly reducing the size of, the instrument.

A still further object of the invention is the provision of resonant means for the various octaves of the scale, especially adapted to the pitch and volume suited to that particular musical area 45 of the instrument's gamut.

Another object of the invention is the production of an instrument, comparable in facility to the great organ, which shall possess throughout a true tonality not only as to its primes but as to all its partials, each and every partial being separately produced under conditions particularly adapted to its own needs, and never sounding outside those conditions.

50 Still another object is the production of an instrument which, size for size, shall enormously

excel the organ in volume, and which shall have as many tonal colors with greater facilities in their use, while possessing only a very small fraction of the parts necessary in organ practice. Furthermore, the instrument herein disclosed 5 is not sensitive to changes in temperature, and is free from tuning needs, up-keep difficulties, sluggishness of speech, impurities of tone, and inability to produce true soft tones.

In addition to the broader features of my invention there are special details of design and of structure, assembly, and co-action of parts which will be hereinafter explained.

An important object of my invention is to provide sensibly simple or fundamental tones having for each manual employed, the eighty-four pitches associated with a seven-octave scale tuned in equal temperament. Where cheapness and compactness are vital factors, these same eighty-four notes may also be used, not only for the 20 pitch-giving primes of all the tones of the instrument, but also, suitably proportioned as to loudness, for all of the other partials contained in its many varied qualities or timbres. This is what I denominate my "borrowing system", and is disclosed in my co-pending application, Serial No. 472,969, filed August 4, 1930, now Patent No. 1,899,884 dated February 28, 1933. It is used in the present case because of its extreme simplicity and cheapness of construction, coupled with a 30 musical efficiency remarkable in so inexpensive an instrument. It should be understood, however, that in more elaborate instruments I prefer to use a non-borrowing system wherein the sounders used as primes are not at the same time used 35 as upper partials, since this affords an even greater musical excellence albeit it is relatively more expensive and complex.

In musical instruments making use of a scale 40 tuned in equal temperament, and depending for the musical pitches of such scale upon rotating members producing pulsations, all such pulsations, including those representing the well-known incommensurate ratios subsisting between certain notes of each octave, can be secured with an accuracy sufficient for all practical purposes by the employment of rotating members having but six different rotative speeds for an instrument of a range of seven octaves. More 45 rotating speeds may be used, and in some cases twelve have been used, but for simplicity and cheapness, the smallest feasible number of speeds of rotation is preferred. For this reason use is here made of the general plant set forth in said application Serial No. 472,969, it being 50 55

understood that where, in this present application, more than six moving members are shown, there are still but six rotative speeds, some of said speeds representing the velocities of a plurality of moving members. These moving members or rotors carry pulsation-producing toothed annuli, and are driven and governed in a manner essentially like that set forth in the aforementioned application.

10 In the drawings:

Fig. 1 is a diagrammatic plan view of the driving and governing means for a three manual instrument, the three lowest octaves of each manual being served by three differently-speeded 15 rotors, each of the rotors serving any manual revolving at the identical speed of the equivalent rotor associated with the other two manuals;

Fig. 2 is a side elevation, illustrating the grouping of the pipes about a rotor serving some of 20 the lower notes of the instrument;

Fig. 3 is a diagrammatic plan view of one of the three treble rotors of the instrument, illustrating the general scheme of arrangement or grouping of some of its sounders;

25 Fig. 4 is an elevation, illustrating the same plan of grouping about the central rotor;

Fig. 5 is a sectional view of certain details of a sounder particularly adapted to the lowest octave of the instrument;

30 Figs. 6 and 7 are respectively, a plan view broken away, and a side view, of a multiplexed sounder especially adapted to serve throughout the range of the second octave of the instrument;

35 Figs. 8 and 8a are respectively side and plan views of a sounder intended to serve the third and fourth octaves of the instrument's range, that is, to and including note No. 49, only those parts necessary to a clear understanding of the device being shown in Fig. 8;

40 Fig. 9 is a side view of a sounder and its resonator, especially well fitted to serve for the next octave of the instrument, that is, notes No. 50 to 61 inclusive;

Fig. 10 is a sectional side view of a sounder 45 suited for the next to the last octave of the instrument's gamut;

Fig. 11 is a side view of a sounder suited to the highest octave of the instrument;

Fig. 12 is a side view of a key of the manual, 50 illustrating the key-contact systems used in an instrument having a plurality of manuals;

Fig. 13 is a diagrammatic illustration of the wiring system associated with one of the manuals, including also the tremolo mechanism;

55 Fig. 14 is an elevation showing details of a three-manual tremolo commutator;

Fig. 15 is a diagrammatic view of a wiring scheme adapted to a three-manual instrument;

Fig. 16 is a diagrammatic view of the operative 60 wiring system associated with the thirteenth key of each of the three manuals, together with the connections necessary to put two of these manuals in control of separate consoles and players for the purpose of multiplexing the instrument.

65 Fig. 17 is a front elevation of the main instrument and its three manuals adapted to control all the sounders when operated by one player, with a detachable console on either side capable, in each case, of controlling the sounders normally associated with one manual of the main instrument, as well as those other sounders which may be rendered operative through certain couplings of manuals.

70 75 Fig. 1 illustrates diagrammatically the place-

ment of the rotors and the driving and governing mechanism for a three-manual instrument. It will be noted that the rotors serving the three lower octaves of the instrument are nine in number, the rotors for the groups of sonorous bodies indicated by the large numerals 1, 2 and 3 serving, respectively, in these three lower octaves all the notes C, C $\sharp$, D and D $\sharp$; all of the notes E, F, F $\sharp$ and G; and all the notes G $\sharp$, A, A $\sharp$ and B associated with one manual of the instrument as, for example, the second or middle manual. Similarly, the rotors for the groups of sonorous bodies indicated by the large numerals 4, 5 and 6 serve, respectively, the same notes of the three lower octaves of another manual, as for example, the upper manual; while the rotors for the groups of sonorous bodies indicated by the large numerals 7, 8 and 9 similarly serve, respectively, the same notes of the remaining manual of the instrument.

20 Instruments of this type are conveniently divided into operative and speaking sections, and Fig. 1 is mainly concerned with the speaking part of the instrument. As the driving mechanism shown in this figure is clearly set forth and described in application Serial No. 472,969 above mentioned, and the governing mechanism is described and claimed in my co-pending application Ser. No. 371,211 filed June 15, 1929, (now Patent No. 1,911,326, dated May 30, 1933), only 30 brief treatment of them is necessary here. A motor 19 drives the belt pulley 11 through the agency of geared mechanism provided with a variable slippage factor consisting of a copper annulus 12 capable of retardation by the inductive action of the braking magnets 13, 14, the one constant and the other intermittent, the intermittent magnet being controlled by a centrifugal contact finger 15, and relay 16 and associated parts.

40 From the under side of the pulley 11 a belt 17 passes about the large pulley 18, thence under the adjustable, belt-tensioning idler 19 and about the large pulley 20. From the pulley 20 said belt 17 passes to the larger pulley 21, from which it 45 passes about the pulley 22, thence about the angularly placed idler 23 and back to the upper side of pulley 11, thus completing the circuit. This arrangement serves to give correctly timed rotation to the three rotors driven by the pulleys 20, 50 21, and 22, said rotors serving the four upper octaves of the instrument throughout its three manuals, for since the sounders for the higher pitches are so much smaller than those for the bass octaves, it is convenient to place about each of the 55 three high speed rotors all of the sounders associated with that rotative speed which are used in the thrice-produced scale of a three manual instrument. In the three lower octaves, with their very much larger sounders, a similar grouping 60 about three rotors is not convenient unless the largest sounders at least, are multiplexed, and in Fig. 1, for clearer showing, I have preferred to show a separate sounder for each of the three notes C, each of the three notes C $\sharp$, and so on 65 throughout the lower three octaves of the instrument.

70 It should be understood, however, that where cheapness and compactness are sufficiently controlling factors, both may be obtained by the employment for the instrument's lowest notes of the multiplexed sounders therefor which will be described later. The lay-out shown in Fig. 1 therefore comprises nine rotors for the three lower octaves of a three manual instrument, while the 75

four upper octaves thereof are served throughout the three manuals by the employment of three rotors only. The three rotative speeds of the nine bass rotors shown are one-fourth those of the corresponding treble rotors, and as clearly set forth in my said companion application Serial No. 472,969, each rotor bears pulsation-producing annuli adapted to generate at each revolution, sixteen, seventeen, eighteen, nineteen, or twice, four, or eight times such numbers of pulsations, thus producing, with the six rotative speeds, all the vibrational frequencies of seven octaves of a scale tuned in equal temperament.

In order to get the slower speeds necessary for the three lower octaves, a belt 24 passes from a pulley 25 to the rotor pulley 26 in the upper row of rotor pulleys, thence about an idler 27 and leftward to an adjustable, belt-tensioning idler 28. From the under side of idler 28 belt 24 passes about the pulley 29 of the rotor for group 5 in the middle of said upper row, and thence to the top of pulley 30 of the rotor for group 8 of said upper row. The belt 24 then passes to the pulley 31 of the rotor for group 7 in the middle row, from which it passes to the pulley 32 of the rotor for group 9 in the lower row; thence to the pulley 33 of the rotor for group 4 in the middle row; thence to the pulley 34 of the rotor for group 6 of the lower row; thence to the pulley for the rotor of group 1; and thence to pulley 35 of the rotor for group 3 of the lower row, from the bottom of which it passes to the bottom of the small pulley 25, thus completing its circuit.

The resonant tubes of the sounders associated with the rotor of group 1 are indicated at 36, 37, 38, 39, 40, 41, 42, and 43. It is to be understood, however, that this showing could just as well represent either of the other two groups in this middle row, since they are all identical, merely serving identical notes of different manuals. Four electromagnets 44, 45, 46, and 47 are associated with sounders 36, 38, 40, and 42, the electromagnets associated with the other four sounders being shown as broken away. The cores of said magnets project into close proximity to pulsation-producing annuli 48 carried by the shaft 49, one of which is shown but without teeth or wave forms owing to the smallness of its size and the fact that all these details are so clearly set forth in my companion applications before mentioned. They will also be briefly referred to again in connection with Figs. 3 and 7 hereof. A belt 50 extends from the pulley 25 to the tremolo-actuating pulley 51, more clearly shown in Figs. 13 and 14.

As set forth in application Ser. No. 472,969, the sizes of the pulleys are so planned with reference to the driving speed that the shafts carrying the lowest notes C of the instrument shall rotate at 121.25 R. P. M. (see group 4), while the shaft carrying the highest notes C shall rotate at four times that speed or 485 R. P. M. The bass shafts carrying the notes E rotate at 152.7654 R. P. M. (see group 5), and the treble shaft carrying the notes E rotates at 611.0617, while the bass shafts carrying the notes G# rotate at 192.4723 R. P. M. (see group 3), and the treble shaft carrying the notes G# rotates at 768.8895 R. P. M.

In Fig. 2 the rotor or shaft 49 associated with group 1 of the sounders is shown in dotted lines, the pulsation-producing annuli 48 carried by said rotor being also shown in dotted lines throughout most of its length. The electromagnets 45, 47 are likewise shown in dotted lines with their cores opposing some of the lower annuli on rotor 49.

As shown in this figure, the resonant tube or

sounder 36, as indicated by the numeral 1 preceded by the letter "N", is designed to give forth note number 1; sounder 37, note number 14; sounder 38, note number 3; sounder 42, note number 2; and sounder 43, note number 13. Shorter 5 resonant tubes 52, 53, associated with notes number 25 and number 26, that is, note C of 129.33 vibrations per second and C# of 137.02 vibrations per second, are likewise seen in this figure. The rotor 49 turns at 121.25 R. P. M., and carries all 10 the notes C, C#, D and D# of the three lower octaves of the instrument commanded by one manual of the key-board. The two other rotors associated with the same vibrational frequencies of the two other manuals of the instrument are identical with this and turn at the same speed. These three rotors of the middle row of the bass are so essentially like those of the other two rows serving the higher letters of the musical octave throughout the bass section of the three manuals, 20 that no further consideration of them is deemed necessary. The resonant tubes are somewhat shorter and, as will be observed in Fig. 1, somewhat smaller of diameter as the pitches rise. The resonant tubes 39, 40, and 41 of group 1 are associated respectively with note number 16, note number 4 and note number 15.

Figs. 3 and 4 illustrate in diagrammatic plan and in elevation, respectively, the grouping of the sounders about the treble rotor 54 revolving at 30 611.0617 R. P. M., said rotor carrying all the notes E, F, F# and G of the four upper octaves of the three manuals of the instrument, each note number shown in the drawings appearing three times, or once for each manual of the instrument. This 35 is made possible without resort to multiplexing sounders by reason of the fact that the higher pitches of the last four octaves can properly be served by much smaller resonant members. An annulus 55 with a small portion of its periphery 40 dentated to illustrate the method of its coaction with the dentated head of the core 56 serving note 41, as illustrated in Fig. 3. It is to be understood that the wave-forms or dentation of the annuli may be of any desired conformation, and 45 may well vary even in the one instrument as between different sections thereof. To avoid annuli of undesirably large diameter and of objectionably high speeds of rotation where compactness is a vital consideration, it has been found 50 desirable to use a "wave-form" so-called, having active portions or "teeth" somewhat resembling those of gears, but preferably with spaces between them occupying much greater peripheral extent than is occupied by the "teeth" or active 55 portions themselves. It is also advantageous to curve or "let off" the peripheries of the "teeth" upon an arc of less radius than that of the annulus, all as set forth in my aforesaid applications. Where a tonal result characterized by sine- 60 wave type of vibration is desired, I find it convenient where space and size are to be minimized, still to retain the gear-like type of active "tooth", rounded as mentioned, and further to modify the result by the flexibly elastic member 57 or some 65 equivalent, as will be shown in later figures hereof; by weighting to round somewhat the "take-hold" and "let-go"; and by the use, in most instances, of resonators as shown herein. In this manner sensibly sine-wave simple tones are 70 secured through the agency of annuli of practicable size even where an annulus carries several scores of "teeth" or "wave-forms". It is distinctly to be understood, therefore, that I do not confine myself to any particular shape of dentation or 75

wave-form of the annuli, as that may be varied to suit conditions as aforesaid.

In Fig. 3 notes numbered 41, 42, 43 and 44 are thrice exhibited, once for each manual of the instrument, their tubular resonators 58 extending upward as shown in elevation in Fig. 4. Below these notes are seen at 59 the radially outward ends of the shorter and different type of resonators used for the thrice exhibited notes marked on the drawings N—53, N—54, N—55 and N—56. It will of course be understood that this rotor 54 serves notes not possible to show clearly in the drawings, each treble rotor of a three manual instrument of this type caring for sixteen notes thrice represented, or forty-eight in all. The housings 63 for the electromagnetic solenoids are indicated in dotted lines, the flexible support 57 for the radially outward end of a core carrying the plunger 57^a co-acting with the opposed resonator being likewise shown in dotted lines. These members may be supported in any suitable manner, no such supports being here illustrated since it would unnecessarily complicate the showing of this figure. In Fig. 4 the annuli 55 are shown partly in dotted lines, all of said annuli in this figure being without wave forms or dentation.

Fig. 5 illustrates a resonant tube 61 suitable for use in connection with the lowest bass of the instrument. This resonator, where compactness is a considerable factor, may be multiplexed in the same manner as the sounders illustrated in Figs. 6 and 7. It is desirable that the lowest notes of an instrument shall have not only very great volume, but also that they shall be capable of marked loudness of utterance, and this construction is directed to this feature. A diaphragm 62 of plunger type is suitably stiffened by ribs 63, and is elastically held in the casting 64 by an annulus or disk 65 of leather or other suitable material, securely clamped to said casting by an annulus 66 screwed thereto. The flexibly elastic members 67, 68 which carry the plunger 62 are shown broken away, and their functions will be fully described in connection with Figs. 6 and 7. It will be noted that the casting 64 forms as it were a perforated floor for the pipe 61, the upper side of the floor being flat and in a horizontal plane, while the under surface with its opening 61^a presents the conformation of the frustum of an extremely obtuse cone, the purpose being to make as efficient a pumping mechanism as possible. The ribbed and leather-hung plunger 62 swinging upon the members 67, 68, and two other similar members not appearing in this figure, moves not as an ordinary diaphragm having its maximum motion in the center, but rather as a plunger with an equally wide movement throughout its area, thus producing a very great effect upon the air. The perforated floor 61^a is shaped and placed so as to permit the most perfect evacuation of air feasible upon the up-stroke, the slant of its lower side serving to prevent any choking action as the air from the outside area is forced into the smaller superficial area near the opening. This results in a pronounced amplification of action and increase of loudness, a most desirable attainment in the case of the lower notes of the instrument, say from numbers 1 to 13 inclusive.

Referring now to Figs. 6 and 7 which show the same structure, the rotor 49 for group 1 of the bass sounders and an annulus 48 carried by the same are here illustrated, a portion of said an-

nulus being dentated as shown opposite the dentated portion 69 of the co-acting core. As shown in my companion applications, and as indicated in connection with the description of Fig. 3 hereof, wave-forms or tooth-like dentations of any desired shape may be employed according to the special exigencies of the case. The resonant pipe 61, plunger 62, and ribs 63 are also seen in Fig. 7. Bent metallic springs 67, 68, 70, and 71, broadest at the ends fastened to the pipe-supporting casting 64 and tapering toward their opposite ends, are secured in a somewhat interleaved fashion to the central stud 74, this construction assuring the to-and-fro motion of plunger 62. To the inner end of stud 74 and within the tube, a variable weight 75, shown in dotted lines in Fig. 7, serves to bring the whole system somewhere near resonance as well as to soften, as aforesaid, the sharpness of the pluck of the energized core when traversed by the teeth of an annulus leaning in type toward those of a gear. This weight 75 may be placed at any convenient part of the system, but, where room permits, it is well to have it intimately associated with the plunger, either inside or out.

A magnet rail 76 normally carrying three solenoidal magnets 77, the central magnet being omitted in Fig. 6 but shown in section in Fig. 7, is supported at 78 as indicated by dotted lines in Fig. 7, the supports 78 being secured to the further side of the tube-supporting casting by screws 79. In Fig. 6 both the magnet-rail 76 and the rotor 49 are broken away better to show the structure and action of a pivoted arm 80 upon the outermost bent metallic spring 70, said arm 80 being secured to said spring 70 at 81 by a link 82, the leverages being so planned that a given movement of its associated core shall give plunger 62 exactly the same traverse as will be given it by the same movement of either of the other cores 40 acting upon it. This pivoted arm 80 rocks at 83 between bearings 84 of the casting 85 secured at 86 to a boss 87 integral with the tube-supporting casting 64. The ring or annulus 66 securely screwed to the main casting with the plunger-supporting leather gasket 65 between it and said casting, is likewise shown in Fig. 7. A trunnioned member 89 rocks about a pivot 90, the threaded inner end of core 91 passing freely through this member, but being prevented from reciprocation by the lock-nuts 92 which serve to adjust the core nearer to or farther from its associated annulus for purposes of voicing. Spiders 93 having corrugated arms elastically support the dentated or rotor-end 69 of the cores 91 so that they may reciprocate freely without contacting their surrounding solenoidal tubes. Disks 94 (Fig. 6), which may well be of aluminum or brass, serve to cover the chambered portions of the magnet-rail occupied by the magnets, the free space 95 (Fig. 6) being usually filled with plaster of Paris or some suitable substance serving both to hold the bobbin rigidly and better to connect it thermally with the rest of the rail while electrically insulating it therefrom. This promotes cooling and keeps the solenoids more efficient, a method of procedure clearly shown in Fig. 10. Washers 96 are placed beneath the radially outermost ends of the spider-arms 93, through which and the disks 94 the spider arms are secured to the magnet-rail, their inner ends being securely fastened to and beneath the expanded core head as clearly shown in Fig. 7.

The parts omitted from Fig. 5 are identical with the corresponding parts of Figs. 6 and 7,

but it will be noted that in Figs. 6 and 7 the resonant tube has no perforated floor but is stopped by the bodily-moving plunger 62, so that any amplification of the tone in this instance is due 5 to the fact that the leverages are so planned that the plunger 62, as shown, moves about two and a half times the distance traversed by the cores associated with it.

Referring to the two spidered cores 91 shown in 10 Fig. 6, it will be seen that the ends of the cores farthest removed from the co-acting annuli reach the flexibly elastic tapered members with which they are associated, and to which they are fastened, at a point to yield about the aforesaid magnification of movement, while the doubly compounded motion of the system associated with 15 the arm 80 is such as to produce the same enlargement. The annulus 48 of Fig. 6, while the nearest to the observer of all the objects of the 20 figure, is shown in dotted lines to avoid obscuring important members beneath it. The plunger-carrying annulus 65 of leather, rubber, or other suitable material is also seen in Fig. 6.

The type of sounder seen in Figs. 6 and 7 is 25 that which I find suitable for a range of the bass of the instrument extending from about note number 14 to note number 25 inclusive, and the pipe being multiplexed as shown, it may well be of large diameter and of great volume.

It will be seen from Figs. 5, 6 and 7 that while 30 there are four elastically flexible, tapered, plunger-carrying members 67, 68, 70, and 71, only three of them are energized by magnets when the greatest possible power is demanded. This four- 35 support system, however, brings the active arms in better relation to the rotor than would a three-arm system. The three magnets as shown are in line, though the center one is omitted in Fig. 6, better to show what lies beneath it. The resonators associated with notes numbers 26 and 40 above, are of a size which will ordinarily permit the grouping of three of each note number, one for each manual, about their respective rotors, even where different manuals are not served in 45 the bass by different rotors, as illustrated in Fig. 1 merely for the sake of clearness of showing.

The operation of the multiplexed pipes shown in Figs. 6 and 7 is as follows:

The three bent metallic springs 67, 68, and 70 50 are capable of energization by the magnets whose cores are attached to them either directly or through the pivoted arm 80, and the inner ends of all four bent metallic springs are connected to the central stud 74 of the plunger forming the reciprocating floor of the resonator tube. When, 55 therefore, the pressure of a key of a manual, as for instance, key number 13 of the first manual, acts through the operative system to energize its associated magnet, the result will be that the co-acting core will be attracted and released by the alternate passage of relatively near and relatively remote portions of the revolving annulus opposing it. These motions will be transmitted 60 through the associated bent, metallic spring to the plunger floor of the resonator tube, thus causing said tube to emit its proper note with an amount of loudness proportional to the amount of current flowing in the energizing coil about the active magnet-core. If at the same time, 65 the same note, number 13, of either or both the other manuals be pressed, care having been taken that the centers of the teeth of all cores thus associated in the multiplexing of a sounder shall simultaneously pass the centers of the teeth of their co-acting annuli, the associated core or

cores will be energized proportionally to the current flowing about them. The associated bent metallic spring or springs will then transmit the energy to the plunger, the result being that the plunger will make longer excursions the more power it receives.

As the energizing solenoidal magnets of a multiplexed pipe are each upon a circuit controlled by a separate manual, it will be seen that a pipe so multiplexed may perform all the functions of 10 three pipes speaking at the one pitch and controlled by three separate manuals, for the use one manual is making of a pipe is no bar to any desired simultaneous use of the same pipe in response to pressure of the corresponding key of 15 another manual.

Considering now Figs. 8 and 8a, which are two views of the same structure, Fig. 8a showing only such parts as are necessary to a full interpretation of Fig. 8, the housing 72 for the solenoidal 20 magnet 77 (shown in dotted lines), is provided with a flange seen at 72a. The metallic C-spring 97 is screwed to this flange, and to the free end of said spring is fastened the casting 98 carrying at the rightward end the ribbed circular plunger 25 62 adapted to beat air into the resonant tube 61. This plunger is secured to the casting 98 by a threaded stud 99 carrying weighting washers 100 of lead or other material, secured between two nuts 101. It is to be understood that while a 30 system of vibration which is more or less "forced" requires nothing for its mechanical movement in the way of weighting or tensioning which would satisfy the exacting needs of musical tuning, yet, notwithstanding this rather wide workable latitude, the nearer true resonance is reached in a system, the greater will be its efficiency and the less "forcing" it will need, a fact which explains one important reason for using weights and proportioning the springs to the work in hand. The 35 resonator tube 61, while it will respond throughout a rather wide range from the standpoint of tuning accuracy, should be proportioned with care to the pitch of the note it produces, in order that its utterance may be sensibly perfect. This 40 system of tone production must not be confused with organ practice where the pitch as well as the quality of the tone is determined by the pipe, for here the pitch is determined outside the pipe, and the quality is made in an entirely new manner. If the resonator does not suit the pitch 45 delivered to it, it will have to be "forced", and will speak less and less efficiently the more it has to be "forced".

A screw 88 (Fig. 8) is threaded into the lower 55 end of core 91, which is slit for a little more than the distance of the thread in order to prevent possible rattling. This screw 88 passes freely through the swinging member 102 which is pivoted upon threaded centers formed on the 60 screw 103 adjustably and securely held in the casting 98 by the check-nuts 104. A threaded thumb-wheel 105 together with a nut 106, serves to position and secure the screw 88 relative to the swinging member 102 and the casting 98, thus 65 serving to adjust the core 91 with regard to its co-acting annulus (not shown in Figs. 8 and 8a).

It will be noted that the casting 98 serves both as an amplifying extension for the C-spring 97, and as the major part of the weight necessary 70 to ease off the attack and let-go where a gear-like form of annulus-tooth is used and an approximately sine-wave form of result desired at the plunger 62. Where this is secured the resonator will do the rest, delivering a full and beau- 75

tifully formed simple tone. This type of sounder, with its relatively large resonator and considerable amplification, is well suited to meet the requirements of the highest of the three bass octaves of the instrument, as well as the lowest of the four treble octaves, covering in all notes No. 26 to No. 49 inclusive, the plunger and resonator sizes being progressively diminished as the pitches rise.

10 In Fig. 9, 72 indicates the housing of the solenoid; 91 the core which as seen at 69, has five dentations or "wave-forms" where Fig. 8 shows but three, while Fig. 11 shows six, the explanation being that, as the pitch of notes rises, the 15 "wave-forms" or teeth are more numerous and nearer together, thus permitting more teeth within the normal space of an enlarged magnet-head. The spiders 93 shown and described in connection with Figs. 6 and 7, and seen also in 20 Fig. 8, are likewise illustrated in Fig. 9. A bent metallic spring 108, preferably of soft steel that it may not retain magnetism, yet may afford a good path for the return lines of force, is secured at its ends to the longitudinally-extended flange 25 72^a of housing 72, the mid-portion of said spring being secured to the lower end of core 91 which passes through the riveted portion 109, and into the central stud of the ribbed plunger 62. An adjustable weight 110 is attached to the core for 30 purposes already clearly set forth. A resonator 61 is shown broken away, to indicate that it may be of any desired length suitable to the different notes served by the various sounders of this type, which type I find well adapted to notes numbered 35 59 to 61 inclusive. The spring 108 is held at both ends, thus making it somewhat less resilient and better suited to vibrations ranging from 548.07 to 1034.61 per second. The notes being of relatively high pitch, do not require a loudness which necessitates mechanical amplification.

Referring now to Fig. 10, the housing 72 for the solenoidal magnet 77 is shown as embedded in an insulating material 95, as previously mentioned in connection with Fig. 7. The core 91, spider 93, and associated parts are also illustrated in Fig. 10, the core head 69 in this instance carrying five narrow teeth intended to oppose an annulus with the considerable number of 50 teeth necessary for so high a pitch as this type of sounder is designed to serve. The flange 72^a of housing 72 is circular in plan, and is adapted to receive the circular and annularly and concentrically grooved member 111 which is firmly 55 clamped, diaphragm-wise, between said flange 72^a and the metal retaining ring 73, which may be of lead so that it may damp the peripheral vibration of the grooved member, concentrating the same, as much as possible, at the thickened 60 innermost area carrying at its center the reduced and threaded end 112 of the magnet core. Metallic washers 113 permit the nut 114 to bind the said innermost area firmly between itself and the shoulder of the magnet core. 115 indicates 65 disk laminae used for weighting, and secured to the core end 112 by a nut 116. The grooved member 111 may be of any suitable material, but I have found a good grade of maple to serve excellently where a simple fundamental tone 70 is desired, as in this case, for even were there faint upper partials, they would be so evanescent as not to be objectionable where wood is used. To ensure the necessary fundamental quality, 75 the member 111 is left thick at its center that

it may vibrate as a plunger, rather than breaking up as a diaphragm might do. This type of sounder is excellent for notes extending from No. 62 to No. 73 inclusive. As these pitches are so high, resonators may ordinarily be entirely dispensed with, the area of the vibrating member 111 furnishing volume quite sufficient for tones which are so incisive.

Fig. 11 shows a construction similar to that of Fig. 10, the magnet flange 72^a being entirely circular in plan but much smaller, and a relatively short, six-toothed magnet-core 91 suitable to the highest pitches of the instrument being illustrated. The lower end of this core is shouldered and thrust through a diaphragm 117, to which it is securely attached by the nut 118, the weighting laminae 115 and securing nut 116 being also shown. The diaphragm 117 is of any suitable material, a ring 119 which may well be of metal as soft iron, being provided to facilitate return lines of force. Screws 120 clamp diaphragm 117 in place. By making the diaphragm of soft steel the resistance of the magnetic circuit will be greatly lessened, permanent magnetization being avoided, while any upper partials that might be present are so high in pitch as to cause no inconvenience whatever. This type of sounder is designed for the highest octave of the instrument, that is, from notes No. 74 to No. 84. These pitches, the lowest of which represents 2,192.26 30 vibrations per second, are so acute as to require a relatively small volume to enable them musically to balance the lowest notes of the instrument, so that the diaphragm of small diameter is of sufficient area, due reference being had to the scale used in the drawings which, in the case of Fig. 11 is approximately one-half size, though I do not of course, limit myself to particular sizes, actual or relative.

Fig. 12 illustrates a slightly modified form of 40 the key-action shown in my companion application, Serial No. 472,969 and described in detail therein. The key-bed 121 is provided with longitudinally extending raised portions 122, 123, from which pins 124, 125 extend upwardly and 45 serve to position or space the keys with regard to each other, in the well-known manner. The essential difference between this figure and the construction of the companion application just referred to is the additional multi-contact block 50 and its associated parts, made necessary because of the plurality of manuals used with the present instrument. A white key of the manual is indicated at 126, the felted key-strip 126^a limiting the upward movement of the keys under the 55 urgency of spring 127. A projection having a screw-eye passed through it, and an adjusting leather nut, are provided at the rear of each key for the purpose of tensioning spring 127, the lower end of said spring being looped about a 60 slanting notched dowel 127^a glued into the rear of the key-bed.

Tongue springs 128, 129 are screwed to said key, these springs being regulated as to their degree of depression by the adjustable screws 130, the 65 shouldered lower ends of said screws passing through the key as shown. Multi-contact blocks 131 are screwed to the key-bed beneath each key, each block being grooved to fit over longitudinally extending positioning strips 132, 132^a, which serve to keep pressed upward in passive position the wire tongues 133 serving as contact members. Current is supplied by cables 135 to the wires passing through the wiring strips 134. 70 75

A continuous metal strip 134^a serves as a common lead or return, as the case may be, since it is immaterial which purpose it serves if other conditions are suitably adjusted. The contact wires 5 from tongues 133 are bent upwardly at their right-hand ends to facilitate wiring into the cables 135 or onto the continuous strip 134^a. One similarly disposed wire of each block 131 is joined to said strip as seen in Fig. 12, the 10 connection being parted to avoid confusion in the drawing and the open ends thereof being indicated at 134^b, 134^c, respectively.

The tongue springs 128, 129, each carry at their lowermost ends a contacting strip 193, 194, preferably of silver, long enough, transversely to the keys, to bridge safely all of the associated contacts 133 lying beneath them, to the number of four in each case, as clearly shown in connection with the five broken-away keys of Fig. 16. Of 20 these two systems of four contacts, one contact in each case serves as a common return as described in said companion application, the other three contacts in each case being wired to the other sides of appropriate magnets in the operative system as later described. The essential 25 point in connection with Fig. 12 is that in this instrument each of the keys of each of the manuals is provided with eight contact-systems, two of which are used as returns.

Fig. 13 illustrates in its upper portion what is termed the "partial-mixing system", as applied to a single manual and its associated speaking magnets, each as shown and described in my co-pending application Serial No. 472,969, but in this 30 instance the tremolo system for a single manual has been added to render more easily understood the system applicable to a plurality of manuals as shown in Fig. 14. 136 (Fig. 13) indicates the speaking magnets, each of said magnets having associated with it the number of the note of the gamut which it controls. Thus the extreme left-hand magnet 136 in this figure controls note #11, the magnet to the right thereof, note #12, the next magnet to the right, note #13, 40 and so on. Associated with each pair of magnets 136 is a resistance 138. The bar 137, assumed in this showing to be movable transversely of its length, affords means for positioning the contact tongues 138^a along the resistance coils 138, thus 45 diagrammatically representing the electrical result attained by the various partial-rockers indicated at 139.

In the center of Fig. 13 are three vertical rows 50 of block-like members with ten blocks in each row, placed wide apart to permit showing the wiring, the central row of said blocks being doubly tipped with silver so that the blocks may contact properly on both sides. The left-hand row of ten contacts in Fig. 13 is brought into electrical connection with the opposing co-acting surfaces of the central row of contacts when key 55 #13 of the manual is pressed and the partial-rocker 139 representing the first partial is in operative position. Similarly, the right-hand row of ten contacts is brought into electrical connection with the opposing co-acting surfaces of the central row of contacts when key #14 of the manual is pressed. Since a seventh partial 60 is omitted in this instrument as shown, a graded "sub-octave" taking its place, and because it is more orderly to start the moving contacts with the "sub", it will be noted that the first partial is crowded up to the second moving contact in 65 each row. It will be seen, therefore, that each 70

speaking magnet 136 (which in shop practice is always designated by the number of the key of the manual normally causing it to speak when such key is pressed) is wired, as shown, from its nearer pole to the second contact of the associated side of a double relay bearing said manual note-number, such double relay bearing a number in accordance with the control of its two actuating magnets by two separate adjacent keys of the manual, as fully explained in my co-pending application, Serial No. 472,969. 10

In order to make clearer the showing of Fig. 13, directions for the wiring of each contact have been noted opposite the outside contacts of the double relay. It will thus be seen that every such contact save only the second in each outside row, invariably sends a wire to an outside second contact of some other double relay, which is always treated with regard to its numbers in such wiring as if it were two single relays of adjacent 15 numbers. To make it clear to which relay the second of each of these contacts is wired, the note number, which is to say the relay number, is indicated on the drawings, together with the letter of the octave representing the note and 20 the number of vibrations normally elicited by the pressure of the similarly numbered key of the manual. For example, considering the left side of the double relay in question, which is 25 designated "Relay #13", the contact marked "2" 30 is for a prime or first partial having 64.663 vibrations per second, represented on the manual by the note C. The next contact marked "3", therefore, will be for the second partial which, 35 being of twice the number of vibrations, represents the note C an octave higher having 129.326 vibrations per second, and associated with the twenty-fifth note of the manual. This third contact will accordingly be wired to the second moving contact of relay #25, the outside rows of 40 contacts of a double relay being thus referred to as "moving". All of the other contacts of the outside rows are similarly wired, it being obvious 45 that in the case of the double relay #15, #16, the numbers applying to relay #15 will be just one number higher than those applying to relay #14 in similar cases. The same procedure will apply to relay #16 so that the entire relay wiring of the instrument may be set down from a consideration of what obtains in the case of one 50 relay, even though it were not a double one.

In the central row of contact tongues in Fig. 13 each of said tongues is to be understood as 55 wired, though not so shown in the drawing, to two adjacent notes upon its associated partial-mixing rocker 139, after the manner clearly set forth in my co-pending application Ser. No. 472,969. For example, the tongue marked "Sub" in the drawings has a wire 140 leading to a rheostat 141 of the particular partial-rocker reserved 60 for this "sub", forty-two wires 140 being provided for an eighty-four note instrument, as indicated in the drawing. From the central contact marked "5" a wire 142 leads to a rheostat 141, the other end of said resistance being connected 65 to a contact tongue 143 serving upon the fifth partial rocker, the forty-first and forty-second notes of the manual. It will be observed that there is another fifth partial rocker 139' and 70 another resistance 143' in parallel with the resistance 143 serving the partial rocker just described, and these two resistances may be of any desired ohmic value. If, therefore, the first described fifth partial-rocker be actuated, the loud- 75

ness of the fifth partials will be determined by the ohmage of the resistances 143, while if rocker 139' is actuated, the resistances 143' will determine the loudness. If both these rockers be actuated together, still another loudness will result from the simultaneous use of the two resistances and the two rockers, as will readily be seen, three different loudnesses of the fifth partial with two rockers and their associated resistances 10 being thus obtained.

This mechanism, by means of which any desired number of differences of loudness may be given to any partial, is fully described in my co-pending application, Serial No. 472,969, and is 15 only set forth here to make the showing more complete.

The tremolo commutator-pulley 51 is suitably propelled as shown in Fig. 1, brushes 144, 145 bearing upon the commutator, which serves as 20 elsewhere described, electrically to connect and disconnect the tips of said brushes alternately, so that when the tremolo knee-swell 146 is pressed rightwardly a resistance, inversely proportionate to the degree of the pressure, shall connect said 25 brushes irrespective of the angular position of the commutator upon which their rightward ends rest. The result is that when section 147 of said commutator passes under the brushes they are short-circuited and the resistance of 30 the line at this point rendered negligible, while, when the commutator reaches the position shown in the figure, the resistance of such portion of the coil 148 as the movement of the knee-swell does not cut out, will be inserted into the line 35 at this point. The knee-swell 146 is positively positioned against a stop 149 by a spring 150, which causes the bifurcated brush 151 having one prong somewhat longer than the other, to rest wholly upon insulation at the right-hand 40 end of drum 152 carrying the coil 148, this coil being traversed by brush 151 when the knee-swell is operated. The pronged brush 151 is carried by a flat slideable bar 153 running in graphited felt bushings, said bar having secured 45 to its leftward end a flexible wire connection 154. Another connecting wire 155 is secured to the leftward end of the helix or coil 148, this wire being suitably secured to the box containing the drum 152 by a binding post or equivalent means. 50 A link 156 serves to connect bar 153 with the innermost extremity of the rod of knee-swell 146.

A flexible contact spring 157 is secured to the left end of the box which houses the resistance drum 152, the left end of helix 148 and of wire 55 156 being secured to this contact spring. To insure perfect and correctly timed contact, the contacting end of spring 157 is adjusted relative to its co-acting contact by a screw 158 passed through an opening in the spring. An angularly 60 bent member 159 is secured to the slideable bar 153, and pushes the flexible contact 157 slightly to the right as member 159 contacts with said tongue under the action of spring 150, thus shutting off the tremolo upon the removal of the 65 player's knee, and cutting out the resistance helix irrespective of the position of the revolving tremolo commutator.

The alternate high and low resistance of the 70 line at this point produces a "shake" or tremolo in the tone, more or less pronounced according to the position of the knee-swell. It is to be understood that in the three manual instrument forming the basis of this application, Fig. 13 applies to each of its manuals, except that the three 75 tremolo commutators may well be on the same

shaft and propelled by one pulley. This arrangement is illustrated in Fig. 14, where the manuals are indicated by the Roman numerals I, II, III, and three pairs of brushes 144, 145 associated with the three commutators, are shown.

Fig. 15 illustrates diagrammatically the speaking magnets and their associated parts, as described in my co-pending application Serial No. 472,969, rendered applicable to a three manual instrument. The speaking magnets 136 are associated with the first manual of the instrument, while the magnets 160 are associated with the operative system of the same manual. The magnets 136^a, 160^a are associated respectively with the speaking and operative systems of the second 15 manual of the instrument, while the magnets 136^b, 160^b are associated with the speaking and operative systems of the third manual of the instrument. The common bars 137, resistances 138, contacts 138^a, and associated parts, serve to 20 illustrate the action of the expression-control systems of the three manuals, these being but reduplications of that shown and clearly described in detail in my companion application, Serial No. 472,969. To avoid a confusion of wires, 25 only the circuits of the speaking magnets are fully shown, those of the magnets of the operative systems being indicated by the plus and minus signs. These magnets are those associated with the same four keys, as for example #13, #14, #15, 30 and #16, of each of the three manuals, and as shown at 161 the speaking magnets are connected together in pairs on one side. Similarly, the central relay contact 162 of each relay serves for 35 both members of its pair of associated speaking magnets, as clearly set forth in my aforesaid companion application. Manual keys 163, 164 of each of the three manuals representing notes #13 and #14 are associated in a pair in each case as aforesaid. The pedal keys 165, 166 correspond 40 to keys #13 and #14 of each of the three manuals when the instrument is "multiplexed" as shown here and in Figs. 16 and 17. The outside relay contacts 167, 168 are connected respectively to one side of speaking magnets 136, forming a pair. 45 As shown in Fig. 13 the relay contacts 162, 167, 168 are but three of a contact system having for each relay thirty contacts, that is, three rows of contacts as shown, but ten deep in a direction not convenient to show in this view.

The electrical placement of the three tremolo systems is schematically shown at 169, 170, 171, each of said devices being essentially like that shown in Fig. 13 with slight modification as indicated in Fig. 14. The partial resistances 141 are 55 more fully shown in Fig. 13, this figure being scarcely more than a multiplication of the system applicable to a single manual of the instrument, with the addition of keys for pedal bass. 172 indicates a source of current and 173 a wire leading from the negative pole thereof. A wire 174 leads from the positive pole of said source and branches into three wires before entering the tremolo systems. Positive wires 175, 176, 177 emerge from the tremolo system and pass respectively to the three common wires 178, 179, 180 of the three partial rocker systems serving the three 60 manuals.

The operation of the system is as follows: suppose key #13 of manual I be pressed, causing the 70 contact point 181 to close with its co-acting contact 182, thus passing negative current to the relay magnet 160 marked "N 13", whose other pole is connected to the positive side of the electrical source of energy. This energizes magnet 160 of 75

the operative system and causes the contact 167 associated therewith, in common with the nine others in the same row but not shown, to contact with the central row of contacts 162 of which only one (associated with this relay) appears in the drawings. Current then flows from source 172 through wire 173 to the expression-control member 133^b associated with the common bar 137 for manual I; thence through the resistance to the branching circuit at 161, whence wires lead to speaking magnets 136 associated respectively with notes #13 and #14 of the first manual. As only the contact block 167 associated with the upper magnet 136 is electrically co-acting with its associated central contact, from which the rest of the circuit via the partial resistance 141, contact member 183, common wire 178 and wire 175 back to source 172, is supplied, only the note associated with the speaking magnet for note #13 of the first manual sounds, which it does with a quality determined by the mixing system, and a loudness determined by the expression-control system. If, now, the pedal bass key 166 associated with note #13 of manual I be pressed, negative current flows from it across the contacts 184, 185, to the self-same magnet 169 of the operative system, the other pole of which is wired to the positive side of the source of current. This energizes said magnet 169, which then acts precisely as before and with the same result. Fig. 13 embodies a schematic representation of a system based upon the use of the multiple relay shown in Fig. 22 of said companion application Ser. No. 472,969. It is obvious, of course, that the type of relay shown at Fig. 20 of that application might be used, but for compactness and cheapness of construction I ordinarily prefer the multiple type herein indicated.

Referring now to Fig. 16, 186 indicates a portion of manual key #13 of a single-manual detachable console designed and adapted, at will, to take the place of manual I of the main three-manual instrument, permitting the operation thereof by a separate player. 187 indicates a portion of manual key #13 of a single-manual detachable console designed and adapted, at will, to take the place of manual III of the main three-manual instrument, permitting the operation of the third manual by a separate player. Jack-knife or multiple connectors 188, 189, join the single manual consoles to the operative systems associated with the responsive manuals in the main instrument. It is obvious that manual II could also be played at a distance from the main console by adding the necessary connections to that end.

To understand clearly the multiplexing system herein described, it should be borne in mind that the manipulating of any of the three manuals of the main instrument energizes appropriate portions of its associated operative system, which system then acts upon the speaking system to cause it to produce the tonal results desired. It is only necessary, therefore, to introduce parallel or equivalent circuits from the keys of the appropriate detachable multiplexing manual to the proper portions of the operative system associated with the same manual in the main instrument, in order to produce by the manipulation of the separate, detachable manual, tonal results identical with those which would be similarly attained by playing the corresponding manual of the main instrument. In the attainment of this end it is only necessary to close the multiple connectors 188, 189, or their equivalents, and this

does not in the least hinder the player at the main instrument from playing these duplicated manuals which are being simultaneously played from the multiplexing system, should there be occasions when he might wish so to do, as might easily be the case in special compositions written for the multiplexed instrument. 5

190, 191, 192 indicate portions respectively of the thirteenth key of manuals I, II, III of the main instrument. Each of the five #13 keys of Fig. 16 is provided with two contact-bridging bars 193, 194, or ten in all. Beneath each of the bridging bars 193, 194 and co-acting therewith, are four contacts preferably silver-tipped spring wires such as indicated at 133 in Fig. 12, the 15 bridging bars just referred to being also illustrated in said figure. In order to avoid unnecessary complications of the drawings, and for the further reason that it has already been clearly shown and described in connection with Fig. 15, 20 the parallel wiring used for the pedal bass is omitted. It is to be understood, of course, that not only the main instrument, but the two detachable consoles, will ordinarily be provided with the usual pedal bass. Three magnets 160 of the 25 operative system are shown associated with manual I; four magnets 160 of the operative system are shown associated with manual II; while six magnets 160 of the operative system are shown associated with manual III in Fig. 16. 30

As already explained, each of the five keys 186, 187, 190, 191, 192 seen in Fig. 16 closes, upon its depression, eight contacts 133, two of which in each case are joined to a wire 195 serving as a return, leaving six contacts for each key for 35 individual uses. Each of these six key-contacts is connected through a multiple switch 196 with one pole of a magnet 160 of the operative system as clearly shown in the figure and as will be more fully described later, the switch 196 being operated by tappet-controlled magnets, one of which is indicated at 197. A common wire 198 connects all the opposite poles of the operative magnets 160 to the source of electric energy 172 serving the instrument. 40

As the detachable consoles represent manuals which operate in the same general manner as the corresponding manuals of the main instrument, it will suffice to explain the action of the main instrument. Considering first the action of key 190 controlling the thirteenth note of manual I, it will be seen that if said key is pressed under the exact conditions shown in the drawings, no tonal result will follow, since each of the multiple switches 196, 196^a, 196^b associated with it is open. 50 Suppose now, the player presses a tappet which through the energization of a switch-operating magnet 197 closes a switch which causes the associated manual keys to respond with the primes associated with their pitch numbers in the scale. 60 In this case this will be the multiple switch 196^a, one contact pair of which is shown opposite magnet 160^c of the operative system associated with manual I. Current will now flow from the source 172 through the common wire 198 to and through 65 the coil of said magnet 160^c, and thence to and through the pair of contacts of switch 196^a. These contacts will now be closed and the current will pass to the silver-tipped key-contact 133^a, thence to the bridging bar 193 which is now pressing upon it, across said bar to the left-hand silver-tipped key-contact 133^b, and thence through wire 198 to return wire 195 and back to source 172. 70 This completes the circuit and energizes the operative magnet 160^c, causing the sounder having 75

a pitch of 64.66 vibrations per second and associated with manual I, to speak. The construction and operation of the magnets 160 of the operative system, of the multiple switches 196, 5 and of the magnets 197 controlling them, is clearly set forth in application Serial No. 472,969, and it is deemed unnecessary to repeat these details here.

Suppose, now, that the player press a tappet belonging to manual I and serving to couple up 10 the operative system. This will immediately energize a multiple switch-operating magnet 197 resulting in the close of the pairs of contacts of the multiple switch 196^b to the left of magnet 160^d of the operative system. The current will then flow 15 from source 172 by the common wire 198 to and through the coil of magnet 160^d, thence to and through its associated pair of contacts in the multiple switch 196^b, and to the silver-tipped key contact 133^c beneath key 190, thence via the 20 bridging-bar 193 of said key which the player is pressing upon it, to the contact 133^b of said key. Current then passes by wire 199 to the return wire 195 and back to source 172, thus completing 25 the circuit and energizing magnet 160^d as aforesaid, which results in eliciting a prime of 129.33 vibrations per second when the thirteenth key of manual I is pressed. It is obvious, of course, that if at the same time operative magnet 160^c is energized, note #13 and its octave, note 30 #25, will simultaneously sound, and if at the same time operative magnet 160 be energized as explained, then notes #1, #13 and #25 of manual I will all sound together. In other words, manual I will be coupled both up and down. It will be 35 noted that what has been described with regard to the lower contacts of key 190 of manual I pertains equally to the same contacts of the same key of the other two manuals shown, and need not be further adverted to in connection with 40 them.

Considering now the upper contacts of key 190 of manual I, we find that the silver-tipped contact 133^d beneath the bridging bar 194 is connected through the closure of the co-acting contact pair of the multiple switch 196^c with magnet 160^e of manual III. Accordingly, as will now be readily understood without further tracing of the wiring, when the key controlling the thirteenth note of manual I is pressed under these 45 conditions, the sounder normally associated with the twenty-ninth note of manual III will speak in response to the pressure of the thirteenth key of manual I, thus eliciting by the pressure of a C-key of manual I, the note E in the octave above 50 associated with manual III. The next upper contact 133^e of key 190 of manual I being similarly associated with magnet 160^f of the operative system associated with manual II, the pressure of this key, when multiple switch 196^d 55 is closed, will cause the sounding of note #25 of the second manual sounders, as will be readily seen by tracing the circuit thus completed. The third silver-tipped contact 133^f of the upper row of contacts for note #13 of manual I, when its 60 proper multiple switch 196^e is closed and the key is pressed, is put into circuit with magnet 160^g of the operative system associated with manual II so that, under these conditions, operation of the thirteenth key of manual I will cause the 65 sounding of note #32 of manual II, which will be G, a musical twelfth above it.

Considering now the key 191 associated with the thirteenth note of manual II, it will be found that its three upper contacts 133^g, 133^h, 133ⁱ, 70 associated with magnets of the operative system,

serve to elicit in the manner already described, the following notes: The first contact, 133^g, causes when proper conditions are supplied, the thirteenth note of manual III to sound, which is a direct coupling to the third manual. The second contact, 133^h, causes the thirteenth note of manual I to speak, which constitutes a direct coupling to the first manual. The third contact, 133ⁱ, causes note #25 of manual III to speak, which is coupling up an octave but on another 10 manual. Similarly, considering the upper contacts of manual III actuated by key 192, the first contact 133^x causes note #29 of manual III to speak; the second contact 133^y causes note #20 of said manual to speak, and the third contact 133^z causes note #47 of said manual to speak. 15

I do not confine myself in these couplings to the various intervals set down, as it is obvious that any desirable musical intervals may be used, the octave relations being those most common, of course, in coupling both up and down. It is also obvious that the note corresponding normally to the key pressed may, in these cases of coupling, be silent or vocal according to the will of the player shown by his use of the multiple switches worked by the tappets through the agency of the switch-rocking magnets 197. 20

Referring to key 186 of the detachable console normally associated with manual I, a return wire 195^a passes through the jack-knife switch 188 and 30 joins wire 195, thus affording a common return for the two right-hand contacts of said key. From the left-hand lower contact 133' of key 186 a wire 200 leads to and through the jack-knife switch 188 and joins, at 201, the lower member of 35 the co-acting pair of multiple-switch contacts 196 associated with the contact 133^a of key 190 of manual I of the main instrument. Under these conditions, the pressure of either of the keys 186 or 190 produces an identical result. 40

For convenience of illustration the individual contacts of the keys in the case of both the main and the detachable manuals are on the sides of the keys nearest each other and the jack-knife connectors, while the common return 195 is on 45 the outside of the keys farthest away from said connectors. This placement, however, is merely for convenience of showing, is quite immaterial, and is only mentioned to avoid confusion which might result from attempting to trace these 50 circuits on the assumption that this change had not been made.

Suppose, now, that the multiple switch 196^b is closed, and key 186 of the detachable console associated with manual I be pressed. Current 55 will then flow from source 172 by wire 198 to and through magnet 160^d, thence to and through the contacts 196^b which are now closed, thence by wire 202 to and through jack-knife connector 188 to lower contact 133'', thence to bridging-bar 193 pressing upon it, via said bar to contact 133''' and wire 203 to return wire 195^a, thence to wire 195 and back to source 172. This completes the circuit and energizes the operative-system magnet 160^d, causing the sounder associated 60 normally with the twenty-fifth note of manual I of the main instrument to speak in precisely the same way as if elicited by the pressure of the thirteenth note of manual I of the main instrument under the same coupling conditions. 65

In Fig. 17 the console 205 of the main instrument is seen, together with its three manuals I, II and III, the set of pedal-keys 209, and expression-control swell-shoes 210, 211, 212. A 70 75

knee-swell 213 operates the tremolo for the main instrument which, by proper switching means, may at will be put upon any one or more of the manuals. Another knee-swell 214 serves as an 5 accent or sforzando device after a manner set forth in co-pending application Serial No. 472,969. 215, 216, 217 indicate rows of tappets associated respectively with the first, second and third manuals of the instrument. Other switching 10 means of well-known organ utility are indicated at 218, and are used here for similar purposes. All of these parts may be of any suitable construction, and it is deemed unnecessary to describe same in detail.

15 Detachable consoles 219, 220 are associated with the first and third manuals respectively, the cables 221, 222 connecting said consoles with the jack-knife switches 188, 189 of Fig. 16. Each of 20 said consoles 219, 220 is preferably provided with 25 all the tappets pertaining to its own manual that are found in the main instrument, and also with its own pedal-bass keys, two knee-swells and expression-control pedal or pedals. The magnets shown at 197 in Figs. 13 and 16 and fully described in my co-pending application, Serial No. 472,969, are operated by the tappets or their equivalents, and their circuits are paralleled in the well-known manner so as to be operable, so far as associated with the manual in question, 30 from the consoles 219, 220 when such are in use as well as from the main instrument. This enables a player on either of the detachable consoles to do everything with regard to the manual associated with his console, that he would be 35 able to do from the corresponding manual of the main instrument were he playing upon that.

The advantages of this system are very great, since it enables a single musician to have all possible command of a three-manual main instrument with three sets of sounders and three distinct partial-mixing systems all controllable from one console, and also permits the attainment of results never before, so far as I am aware, made possible upon a single instrument. By multiplexing 40 this instrument through attaching to it the extra consoles, it becomes possible for three players to use it simultaneously for elaborate orchestral scores, one, for example, playing the qualities of the stringed instruments, another 45 those of the wood-wind, and a third those of the brass instruments, while a fourth player, not operating a console, may handle the "traps", thus making possible astounding orchestral effects.

50 In Fig. 17 I have shown the main instrument raised and the detachable consoles of as low a construction as possible, so that the player at the main instrument may be seen by the other operators, and act as leader. When it is considered 55 that each manual of the instrument may be fully equipped to produce all the instrumental qualities of the orchestra, it will be seen that players of the multiplexed instrument who perhaps have been playing strings, wood-wind and brass respectively, may at a moment's notice for a tutti 60 passage, all change to the same or any other tonal timbre, with a result which may easily be imagined by the trained musician. The possibility of several players simultaneously playing the 65 one instrument gives opportunity for musical compositions hitherto unwritten, and symphonic effects never before approached by any single instrument.

70 While my particular method of synthetic tone-production lends itself ideally to this multiplexing

extension of the possibilities of a musical instrument, I do not wish to confine myself to the multiplexing of instruments constructed upon this particular plan, for it will be evident that my general plan could be used to multiplex wind instruments of the organ type, or any type of instrument equipped with any type of sounder capable of manipulation from a key manual other than that of the ordinary manual of the instrument commonly associated with it. An instrument of this sort having great power, it is essential that its bass resonators shall be able to vibrate considerable masses of air. In other words, the bass resonators must be of relatively large dimensions sectionally as well as longitudinally. Where compactness and cheapness are vital factors, I resort to a multiplexing of the lower sounders as already shown and described. There are several ways of doing this and I consider my invention to cover them all, but I prefer the use of separate cores and separate energizing coils as shown herein. I am of course aware that the coil surrounding a given magnet core might be wound in a plurality of sections, each one associated with the correct note of its own manual, and all energizing the same core and same sounder. This, however, is open to the objection that such multiple winding makes ordinarily for a low efficiency of magnetization. I have also devised other ways of multiplexing 30 a sounder, but I do not consider any of them as good as that shown, merely mentioning them that it may not be thought that I am unaware of their existence.

It is also to be understood that in the more elaborate types of instrument not using what I have denominated a "borrowing system", any sounder having a plurality of utterances at a given pitch may have certain thereof exclusively reserved for use as partials other than the prime. 40

This invention makes it possible to obtain from one instrument a musical result sensibly equivalent, and in some respects even superior, to that which can be produced by three such instruments without the use of this invention. It gives to 45 each of a plurality of players separated far enough for perfect freedom of action, the command of as much of the whole instrument as he could properly use if seated within reach of all of its manuals, and it gives to the plurality of 50 players an easily attainable musical perfection impossible to any number of players seeking to operate the main instrument directly. It is the use of one instrument to attain the musical results heretofore requiring a plurality of instruments, in a manner analogous to the use in multiplex telegraphy of one wire to produce the results otherwise requiring several wires, which I denote multiplexing in this application. 55 It should be borne in mind that since each separate console of the multiplexed instrument has its own expression means, it is possible for a player, seated at a single-manual multiplexed instrument constructed along the lines of this invention, to play middle C at, say one-third its volume, and 60 while holding it down to have the second player at a separate console, cut in on the same note with a distinctly audible middle C coming from the same sounder and definitely distinct from the sound produced by the first-mentioned player, 65 and while these two tones are sounding in unison, to have the third player cut in with the same distinctly audible note with an added volume making its inception as definite as if played on another instrument. This is brought about by the 70 75

pedal resistances coming in in parallel, and so increasing the strength of the sounder magnet associated with this note. It is also possible for a second or third player at one of the single-manual multiplexed instruments, to sound primes corresponding to keys under the very hands of the first player at the time, notes whose keys could not possibly be reached if the second and third players were seated beside the first player.

10 It is further possible by this invention to play all the four voices through one of the single-manual instruments, whereas this would be impossible no matter how many players might be seated at the main console.

15 I wish also to make it clear that in a powerful instrument of the kind herein set forth, a properly worked out scale dictates, if the best results are to be attained, frequent changes in the type of sounder as the pitch of the notes served by the sounders rises, permitting the volume of the tones to be decreased according to the well-known values subsisting between high and low tones. For this reason I have thought it expedient to illustrate these most desirable types, and 20 to indicate the ranges of tone over which each may well be used, though of course I do not limit myself to the exact ranges given as the limits are naturally somewhat elastic, a few notes either way not being fatal, even if not giving the most 25 ideal results, and I consider these various sounders an integral part of my invention.

There is still another advantage of my system of tone-production too important to be overlooked. So far as I am aware all other keyed instruments now in use are tuned in equal temperament as to their primes, and owe their timbres to these primes being associated with certain other partials which are not tuned in the same temperament and do not, therefore, produce 30 ideally smooth results. In my system, however, all the upper partials as well as the primes of all tonal qualities are in the one temperament, thus leading to a perfection of result not otherwise attainable. As every sounder used is planned 35 for service as a prime, and is only called upon to produce one simple tone at the one pitch, notwithstanding its use for upper partials in tones having primes below this pitch, it is possible for the first time in keyed instruments, so far as 40 I know, to produce tones of any conceivable composition, all of whose partials are perfectly formed, chosen, and graded entirely at will, and without those limitations which have heretofore beset makers of musical instruments.

55 While the pulsation-producing members 48 are shown as annuli, and will preferably be made in annular or ring form, it is obvious that they may be complete disks suitably separated from one another and permanently united to form an extended rotor.

I do not confine myself to the particular manner of initiating tone herein shown, nor to this exact way of controlling tone color or timbre, as I have elsewhere shown several other ways any of 60 which, suitably designed, might be similarly used in the system of multiplexing manuals shown herein.

No claim is herein made to an instrument producing compound tones, the partials of which 65 are all in one temperament, nor to the special types of sounders disclosed, the same being now claimed in a divisional application, Serial No. 719,948 filed April 10, 1934, pursuant to official requirement.

75 What is claimed is:—

1. In a musical instrument, tone-producing instrumentalities responsive to the operation of a plurality of manuals, and means whereby said tone-producing instrumentalities may be operated at will by any or all of a plurality of players 5 at a plurality of separate consoles.

2. In a multiplexing musical instrument, a console having one or more manuals normally associated with and serving to operate one or more sets of tone-producing instrumentalities; 10 and an additional associated console directly connected with said tone-producing instrumentalities and operable at a distance sufficient to permit its simultaneous use by a separate player, and serving to control at will the same tone- 15 producing instrumentalities.

3. A multiplexed musical instrument comprising, in combination, means for generating simple tones; means for combining said simple tones into complex tones of the desired pitch and quality; 20 a plurality of consoles equipped with key-manuals, one of said consoles having a plurality of said manuals; and means for operating said key-manuals from a distance sufficient to permit simultaneous playing of music by a plurality of 25 performers.

4. In a musical instrument, in combination, a plurality of sets of tone-producing instrumentalities, the several sets tuned to a common scale; a plurality of consoles each equipped with a 30 key-manual; and means for simultaneously operating each set of tone-producing instrumentalities from any of said consoles and by a different player.

5. A multiplexed musical instrument comprising, in combination, a plurality of sets of tone-producing instrumentalities, each set tuned to a musical scale; a plurality of consoles equipped with key-manuals, one of said consoles having a plurality of such manuals; means operable 40 from each console for generating through said tone-producing instrumentalities, simple tones; means for selecting and combining said simple tones into complex tones of the pitch and quality desired; expression-control means operable from 45 each console; and means available at will for playing said instrument from all of said consoles by a plurality of performers.

6. A multiplexed musical instrument comprising, in combination, a plurality of sets of tone-producing instrumentalities, each instrumentality capable of producing vibrations of simple waveform to be synthetically combined to produce complex vibrations resulting in tones of the desired pitch and quality; and a plurality of consoles equipped with key-manuals, to produce from a single tone-producing instrumentality the partials of all of the various compound tones having the pitch of said tone-producing instrumentality. 55

7. A musical instrument operable simultaneously by a plurality of players, from a plurality of consoles placed at a plurality of locations.

8. A multiplexed musical instrument comprising, in combination, main and auxiliary consoles and a plurality of manuals; separate sets 65 of tone-producing instrumentalities, each set directly controllable by different performers at any one or more of said consoles and all said sets simultaneously operable from the main console; accurately timed means individual to each 70 note of the gamut of the instrument for producing components of sensibly simple wave-form to be used as elements of compound tones, at all the periodicities of the instrument's range; electrical means responsive to the keys of the main 75

and auxiliary manuals of the instrument and to the tappets or stops thereof, for selecting, grading and combining said simple components into compound tones of the desired timbre; means for simultaneously playing any of said manuals at will; and expression-control means operable from each console of the instrument.

9. A multiplexed musical instrument comprising, in combination, a plurality of consoles and a plurality of manuals simultaneously playable by different performers; rotors carrying annuli; magnetic means associated with each annulus and serving to produce pulsations of predetermined periodicity; means for revolving said rotors and annuli at constant predetermined speeds, the peripheries of said annuli being formed to set up through the action of said magnetic means, rhythmic vibrations of sensibly sinusoidal wave-form, thereby eliciting throughout the gamut of the instrument sensibly fundamental tones of predetermined pitch; means for simultaneously playing any or all of said manuals at will; and expression-control means operable from each console of the instrument.

25 10. A multiplexed musical instrument comprising, in combination, a plurality of consoles and a plurality of manuals simultaneously playable by different performers; rotors carrying annuli; magnetic means associated with each annulus and serving to produce pulsations of predetermined periodicity; means for revolving said rotors and said annuli at constant predetermined speeds, the peripheries of said annuli being formed to set up, through the action of said magnetic means rhythmic vibrations of sensibly sinusoidal wave-form, thereby eliciting throughout the gamut of the instrument sensibly fundamental tones of predetermined pitch; means for simultaneously playing any or all of said manuals at will; expression-control means operable from each console of the instrument; and a plurality of tremolo mechanisms likewise operable from each of said consoles.

11. A multiplexed musical instrument comprising, in combination, main and auxiliary consoles and a plurality of manuals; separate sets of tone-producing instrumentalities associated with the main console only, but directly controllable by different performers at any one or more of said consoles, certain of said tone-producing instrumentalities being adapted to produce fundamentals of tones for which other of said instrumentalities furnish the upper partials to be combined with said fundamentals to produce the desired compound tones; timed rotors carrying annuli; magnetic means associated with said annuli to produce pulsations to be translated into tone; means for combining said fundamen-

5 tals and selected partials to produce the desired composite tones; means whereby different performers may simultaneously play the manuals of the main and of the auxiliary consoles; and expression-control means operable from each console of the instrument.

12. A multiplexed musical instrument comprising, in combination, main and auxiliary consoles and a plurality of manuals; separate sets of tone-producing instrumentalities, each set directly controllable by different performers at one or more of said consoles, each instrumentality of each set being associated with an individual note of its manual; timed rotors carrying formed annuli; magnetic means associated with each annulus and adapted therewith to produce rhythmic vibrations of a periodicity identical with that associated with the particular key of the manual with which it is in operable connection, thereby eliciting throughout the range of the instrument, sensibly fundamental tones of predetermined pitch; magnets associated with the tone-producing instrumentalities of the instrument and operable by different performers from any or all of said manuals; expression-control means for regulating the tonal output of said magnets; and a plurality of tremolo mechanisms, each operable from any manual of the instrument.

13. A multiplexed musical instrument comprising, in combination, a plurality of consoles and a plurality of manuals playable by different performers; separate sets of tone-producing instrumentalities associated with the main console only but directly controllable by any of said manuals, each set associated with a section of the gamut of the instrument individual to itself; timed rotors and magnetic means associated therewith; pulsation-producing annuli, one associated with each of said tone-producing instrumentalities and adapted through the action of said magnetic means to set up rhythmic vibrations in said instrumentalities, thereby eliciting throughout the range of the instrument, sensibly fundamental tones of predetermined pitch; a plurality of contacts associated with each key of each manual of the instrument; magnets operable by the closure of said contacts upon depression of the proper key of any of the manuals to sound the selected tone-producing instrumentalities; switching means for operatively connecting said auxiliary consoles and said main console at the will of the performer; and means connected with each auxiliary console for playing by different performers, any or all of the tone-producing instrumentalities associated with the main console.

MELVIN L. SEVERY.
